SPACE DISCHARGE DEVICE

Ellison S. Purington, Gloucester, Mass., assignor
to John Hays Hammond, Jr., Gloucester, Mass.

Application July 6, 1939, Serial No. 283,019

4 Claims. (Cl. 250—27.5)

This invention relates to space discharge devices and more particularly to vacuum tube devices for operation at very high frequencies.

The invention further relates to a vacuum tube device in which is incorporated two sets of electrodes which are connected in a substantially fixed oscillatory circuit.

The performance of a vacuum tube with a given structure of cathode, grids and plate hitherto has been limited because of the inferior properties of the inductance circuit from plate to cathode through the plate lead, external inductor, external by-pass condenser and the cathode lead.

In the present invention, the performance for a given structure of cathodes, grids and plates is very greatly improved by designing the system for the specific frequency desired, with substantially all the magnetic energy of the oscillatory circuit associated with a suitable coil-type inductor built within the tube itself. Preferably a dual electronic structure is used, with push-pull operation, and with the coil-type inductor bridging between the plates of the two electronic structures. The inductor may be suitably center-tapped for plate power supply, and may be tapped for connection to a low impedance external transmission line. The plates may be provided with external leads for connection to external impedances to provide for fine adjustment of the oscillatory circuit.

The invention also consists in certain new and original features of construction and combinations of parts hereinafter set forth and claimed.

Although the novel features which are believed to be characteristic of this invention will be particularly pointed out in the claims appended here-to, the invention itself, as to its objects and advantages, the mode of its operation and the manner of its organization may be better understood by referring to the following description, taken in connection with the accompanying drawings forming a part thereof, in which

Fig. 1 is a longitudinal sectional view illustrating the general structure of a tube embodying the present invention;

Fig. 2 is a transverse section taken on line 2—2 of Fig. 1;

Fig. 3 is a longitudinal section similar to Fig. 1 illustrating the general structure of a modified form of tube; and

Fig. 4 illustrates diagrammatically a transmitting circuit including tubes of the types depicted in Figs. 1, 2 and 3.

Like reference characters denote like parts in the several figures of the drawings.

Referring to the accompanying drawings and more particularly to Figs. 1 and 2, a tube structure is shown which comprises a base 11, a cap 12 and a tube 13 mounted between the base and the cap to form an envelope. Fused to the top and bottom of the tube 13 are presses 15 and 16 respectively. Mounted in the base 11 are six prongs 17—22. The prongs 18 and 21 are connected to rods 25 and 26 which support the ends of filaments 27 and 28 respectively. The other ends of the filaments 27 and 28 are supported by a branched rod 29. The rod 29 is connected to the prong 20 which is used as ground.

The prongs 17 and 22 are connected to rods 30 and 31, supporting the first grids 32 and 33 which surround the filaments 27 and 28 respectively. The second grids 35 and 36 are connected together and to a rod 37 which in turn is connected to the prong 19. The third grids 38 and 39 are supported by the branched rod 29. Condensers 40 and 41 are connected across the filaments 27 and 28 and a condenser 42 is connected between the grids 35 and 36 and the branched rod 29.

Mounted in the cap 12 are four prongs 45—48. The prongs 45 and 48 are connected to rods 49 and 50, supporting cylindrical plates 51 and 52 which respectively surround the two sets of grids and filaments. Connecting the two plates 51 and 52 is a coil 53 the center point of which is connected through a coil 55 to the second grids 35 and 36 and to the prong 37. The prongs 46 and 47 are connected to rods 56 and 57 which in turn are connected to the coil 53 at suitable points.

The two sets of electrodes are preferably arranged symmetrically within the casing and with respect to the connecting leads and prongs. More than two sets may be used in certain instances, using a symmetrical arrangement. Suitable supporting members may be provided in addition to those shown but they should be of insulating material so as not to affect the operation of the tube. The condensers 40, 41 and 42 are also symmetrically arranged and may be symmetrically located in the casing. They have been represented diagrammatically for convenience.

The casing may be of metal, glass or other standard construction provided the electrodes and leads are arranged generally as disclosed herein.

Referring to the modified form of the invention depicted in Fig. 3 a tube structure is shown which comprises a base 61, a cap 62 and a tube 63 mounted between the base and the cap. Fused

to the top and bottom of the tube 53 are glass presses 65 and 66 respectively. Mounted in the base 61 are four prongs 67-70. The prongs 67 and 70 are connected to rods 71 and 72 which support the ends of filaments 75 and 76 respectively, the other ends of which are supported by a branched rod 77. The rod 77 is connected to the prong 69, which is used as ground. Surrounding the filaments 75 and 76 are cylindrically shaped cathodes 78 and 79 respectively, which are supported from the branched rod 77.

Mounted in the cap 62 are five prongs 80-84. The prongs 80 and 84 are respectively connected by rods 85 and 86 to cylindrical plates 87 and 88. The prongs 81 and 83 are respectively connected by rods 89 and 90 to grids 91 and 92 which surround the cathodes 78 and 79.

Connecting the two plates 87 and 88 is a coil 93. Mounted concentrically within the coil 93 but insulated therefrom is a second coil 95 the ends of which are connected respectively to the rods 89 and 90. The center point of the coil 95 is connected by a rod 96 to the prong 82 and through a condenser 97 and a resistor 98 in parallel to the rod 77. The center point of the coil 93 is connected through a condenser 99 to the rod 77 and through a rod 100 to the prong 68. Condensers 101 and 102 are connected between the rods 71 and 72 respectively and the rod 77.

The tubes shown in Figs. 1-3 may be used in various high frequency circuits as oscillators or amplifiers. One circuit illustrating the use of such tubes is shown in Fig. 4. This circuit includes a master oscillator 105, a power amplifier 106 and a radiator 107.

The master oscillator 105 is shown as comprising a duo-triode tube 108, which may be of the type depicted in Fig. 3, the plates 87 and 88 of which are connected together through variable condensers 109. The power amplifier 106 is shown as comprising a duo-pentode tube 110, which may be of the type illustrated in Figs. 1 and 2, the first grids 32 and 33 of which are connected to the grids 91 and 92 of the tube 108.

The second grids 35 and 36 and the center of plate coil 53 of the tube 110 are connected through a transformer 111 to the output circuit of a modulator 112. Plate power may be supplied by a source 111a. The input circuit of the modulator 112 is connected to the output circuit of a speech amplifier 113 the input circuit of which is connected to a microphone 115. The plates 51 and 52 are connected together through a variable condenser 116. Points on the coil 53 are connected to the two arms of the antenna 107, located suitably distant from tube 110.

In the operation of the transmitter shown in Fig. 4, the low power oscillator in conjunction with the vernier condensers 109 generates the desired frequency, determined by the inductor element 93, and the capacitor element comprising the two plate-cathode capacitances in series, bridged by the vernier condensers 109 in series. The feed back is by the grid coil 85 suitably magnetically coupled to coil 83, and connected to the grids of the tube. Oscillatory energy is coupled from the oscillator 105 to the amplifier 106 by direct connection of grids 91 and 92 of the tube 108 to grids 32 and 33 of the tube 110, bias for both sets of grids being determined by the grid circuit resistor within tube 108. Plate and second grid power for the amplifier tube 110 is supplied from a common source including the plate battery 111a and transformer 111. Condenser 116 is adjusted for 75

best conversion of this power to high frequency output power. Transformer 111 serves to introduce modulatory energy from the modulator circuits 112, actuated from speech amplifier 113, which in turn is actuated by microphone 115. The output high frequency oscillatory power is delivered from symmetrically located taps on coil 53, to a radiating system 107 comprising two quarter wave portions with the transmission line from coil 53 of well known proper length for best utilization of the amplified power produced by tube 110.

This specific circuit has been shown only for purposes of illustration. Other circuits could be readily devised, for example using a tube of the type 110 as a crystal controlled oscillator driving a similar tube as a continuous wave telegraphic amplifier. By using suitably coordinated tubes of the general type indicated the construction of transmitters for very high frequency purposes may be made in a simple manner, with easy adjustment and with reliable circuit operation. The tube 108 may be designed to have a natural frequency just above the desired frequency, final adjustment to the desired frequency being obtained by the condensers 109.

A pair of sets of electrodes symmetrically arranged is suitable for push-pull operation or for operation in parallel. A single set of electrodes may be used, however, with the tuning coil connected from plate to a by-pass condenser connected to the cathode and all built within the envelope as abcve indicated. In general, the invention contemplates enclosing all possible tuning and connecting elements within the tube envelope and so mounting the same that all leads are maintained as short as possible. This is particularly important for very high frequencies where the inductance and capacity of long leads would prevent proper operation. By concentrating the inductance within the coils in the tube itself, a maximum transfer of energy and high efficiency of operation is obtained.

It is to be understood that standard sources of potential, filters, controls, etc. may be used. Only so much of the circuit details have been shown as is necessary to an understanding of the invention. Furthermore, the invention is not to be limited to the specific embodiment shown herein. Various changes and modifications may be made therein as will be apparent to a person skilled in the art. The invention is only to be limited in accordance with the following claims.

What is claimed is:

1. A space discharge device adapted for high frequency operation comprising an envelope having a base member at each end, a plurality of sets of electrodes disposed within the envelope, each set comprising at least a cathode, grid and anode, an inductance coil within the envelope interconnecting corresponding electrodes of said sets and forming with the interelectrode capacities an oscillatory circuit resonant approximately to the operating frequency, terminal pins carried by each base member, connections from certain of the terminal pins of one base member to certain of the electrodes whereby energizing current and potentials may be supplied thereto, a connection from another terminal pin of said base member to the mid-tap on the inductance coil, said last mentioned connection including a second coil, and connections within the envelope to the terminal pins of the other base member whereby the operating frequency may be supplied to an external utilization circuit.

2. A space discharge device as defined in claim 1 wherein each set of electrodes includes a screen grid, and connections from said screen grids to that end of the second coil to which the terminal pin is connected.

3. A space discharge device adapted for high frequency operation comprising an envelope having a base member at each end, a plurality of sets of electrodes disposed within the envelope, each set comprising at least a cathode, a signal grid, a screen grid and an anode, an inductance coil within the envelope interconnecting the anodes of said sets and forming with the inter-electrode capacities an oscillatory circuit resonant approximately to the operating frequency, terminal pins carried by each base member, a connection from each signal grid to its respective terminal pin of one base member, the screen grids being connected together and to another

5 terminal pin of said one base member, a coil connected between said common connection and the mid-tap on the inductance coil, and connections from symmetrical points on said mid-tapped inductance coil to terminal pins of the other base member whereby the operating frequency may be supplied to an external utilization circuit.

10 4. A space discharge device as defined in claim 3 wherein a separate connection is provided between each cathode and a terminal pin of said one base member, and a common connection is provided between said cathodes and another terminal pin of said one base member, and condensers connected respectively between each separate cathode connection and the common cathode connection and between the common screen grid connection and the common cathode connection.
